UNITED STATES PATENT OFFICE.

THEODORE HUSS, OF SAGINAW, MICHIGAN, ASSIGNOR TO THE ARGO ELECTRIC VEHICLE COMPANY, OF SAGINAW, MICHIGAN, A CORPORATION OF MICHIGAN.

DESIGN FOR A VEHICLE-BODY.

41,355.

Specification for Design.

Patented May 2, 1911.

Application filed September 13, 1910. Serial No. 581,908. Term of patent 7 years.

To all whom it may concern:

Be it known that I, THEODORE HUSS, a citizen of the United States, residing at Saginaw, in the county of Saginaw and State of Michigan, have invented a new, original, and ornamental Design for Vehicle-Bodies, of which the following is a specification, reference being had to the accompanying drawing, forming part thereof.

Figure 1 is a perspective view looking at the rear of the body; and Fig. 2 is a perspec-

tive view looking at the side and front of the body.

I claim:

The ornamental design for a vehicle body, as shown.

Signed by me this 9th day of September, 1910.

THEODORE HUSS.
